UNITED STATES PATENT OFFICE

163,768

PLATFORM WEIGHING SCALE

Seldon Spencer Ridenour, Rock Island, Ill., assignor to Fairbanks, Morse & Co., Chicago, Ill., a corporation of Illinois

Application February 6, 1951, Serial No. 14,111

Term of patent 14 years

(Cl. D52—10)

To all whom it may concern:

Be it known that I, Seldon Spencer Ridenour, a citizen of the United States, residing at Rock Island, State of Illinois, have invented a new, original, and ornamental Design for a Platform Weighing Scale, of which the following is a specification, reference being had to the accompanying drawings, forming a part hereof.

In the drawings:

Fig. 1 is a top plan view of a platform weighing scale, showing my new design;

Fig. 2 is a front view;

Fig. 3 is an end elevational view as seen from the right-hand end thereof;

Fig. 4 is an elevational view of the opposite end, and

Fig. 5 is a rear view.

The characteristic features of my design reside in the portions shown in full lines.

I claim:

The ornamental design for a platform weighing scale, as shown and described.

SELDON SPENCER RIDENOUR.
